UNITED STATES PATENT OFFICE.

EUGENE SMITH, OF PHILADELPHIA, PENNSYLVANIA, ASSIGNOR OF TWO-THIRDS TO THOMAS H. TAYLOR, OF WILMINGTON, DELAWARE.

SHOE-SEWING MACHINE.

SPECIFICATION forming part of Letters Patent No. 767,666, dated August 16, 1904.

Application filed August 8, 1901. Serial No. 71,325. (No model.)

To all whom it may concern:

Be it known that I, EUGENE SMITH, a citizen of the United States, residing at Philadelphia, in the county of Philadelphia and State 5 of Pennsylvania, have invented certain new and useful Improvements in Shoe - Sewing Machines; and I do hereby declare the following to be a full, clear, and exact description of the invention, such as will enable others 10 skilled in the art to which it appertains to make and use the same.

This invention relates to sewing-machines, and particularly to machines which make a lock-stitch.

15 The object of the invention is to provide a machine for sewing welts to the uppers and insoles of boots and shoes and also for stitching the welts to the soles which will make a strong and durable seam and will be simple 20 in its parts and operations.

The features of novelty will be hereinafter described in detail and then pointed out in the clauses of the claim.

In the drawings accompanying this description, Figure 1 is an elevation of the right-hand side of the machine, parts being shown in sections. Fig. 2 is a top plan. Fig. 3 is a front elevation. Fig. 4 is an elevation same as Fig. 1, showing the parts in different position. Fig. 5 is an elevation of the left-hand side of the machine, a portion of the cam-disk A being broken away to show clearly the conformation of the groove for actuating the awl. Fig. 6 is a plan showing in detail the awl mechanism, and Fig. 7 is a front elevation showing portions of the awl-actuating mechanism in detail.

The frame of the machine is designated generally by F and has at each side thereof 40 an angular extension f. The main shaft S is supported by and journaled in said extensions at the angle thereof, and a counter-shaft s is journaled in the free ends of said extensions. The frame also has an upright f' at the front 45 in and by which certain parts are journaled and supported, as hereinafter described.

Two disks A and B are suitably secured to, so as to rotate with, the main shaft. The disks embody all the various cam-grooves

which are instrumental in actuating the several parts of the machine. The counter-shaft affords a journal for and supports the needle, take-up, and hook-actuating levers.

Journaled in the upright f' is a tubular shaft n, having near the outer end two arms, 55 the one n' having suitably clamped thereto a curved hooked needle n² and the other, n³, being connected by a link n⁴, journaled, as stated, and carrying between its ends a roller, which travels in the cam-groove n⁶ of disk B. The 60 needle is arc-shaped and has its hook on the outside of the arc. The tubular shaft n is cut away at n⁷ both circumferentially and longitudinally to a considerable extent for the purpose of permitting the independent 65 movements of the awl-carrying shaft, as hereinafter explained.

The take-up lever is indicated by t, is journaled, as stated, and carries a roller between its ends, which travels in the cam-groove t' 70 of disk B. The lever t has journaled in its outer end a thread-truck t², around which the needle-thread n⁸ runs to the looper l.

The oscillating hook h, which takes the loop of needle-thread and passes it around the bobbin-case containing the lower or locking thread, is formed on and projected radially and laterally from a carrier or disk h', secured in any suitable way to the outer end of a short shaft h², journaled in a bracket h³ of the upright f'. 75 The inner end of the shaft h² has secured to it a pinion h⁴, with which meshes a segmental rack h⁵ on the free end of a lever h⁶, journaled, as stated. Lever h⁶ carries a roller between its ends which travels in the cam-groove h⁷ in 80 the disk A. The projection of the hook h, as above stated, is to locate the same in a plane parallel with and closely beside the needle and also centrally of the bobbin-case and beyond 85 its periphery.

The looper l for manipulating the needle-thread so that it will be placed in the hook of the needle is supported and guided by two screws l' in the side of the upright f', near the top thereof. The shank l² of the looper 95 is slotted at l³ for co-operation with its supporting-screws and is connected by a pin at its rear end with a slot in the upper end of a ver-

tical lever l^4 , pivoted to the frame at l^5 , and carrying between its ends a roller which travels in a cam-groove l^6 in disk A. The looper has a thread-guiding aperture in its outer end, 5 which latter is extended horizontally from the downwardly and outwardly and laterally extending portion l^7 of the shank. The particular conformation is given to the shank of the looper in order to locate the same beside the 10 path of the needle and just below the upper limit of its movement. The thread n^8 from the supply extends between the two jaws of a thread-grip G over a thread-guiding truck g, journaled in or near the wax-pot g^9 , under another truck g^{10} , near the bottom of said pot, 15 up through a stripping-guide g^{11} at or near the top of said pot, over the truck t^2 on the end of the take-up lever, and thence downwardly to and through the end of the looper l^7 .

20 The work-rest is shown at W and is supported by an arm secured to the front of the upright f^1 . Such rest extends into the path of the needle and awl and is provided with an enlarged opening w for the passage of the 25 needle and awl and to permit of the lateral or feed movement of the latter.

The bobbin-case b is of ordinary form, has a thread-aperture in the periphery thereof, and is supported in place against the face of 30 the disk h^1 by a holder b' of cup shape, having a bobbin-case-supporting ledge h^2 . The holder is hinged to a bracket-arm b³ on the frame and is held vertically in place by a spring or rigid latch b⁴, held by a screw b⁵, tapped into 35 the bracket-arm.

W' is a welt-guide suitably supported on the upright f^1 , which guides the welt to the stitching-point.

The thread-grip G consists of a stationary 40 jaw g^4 , carried by a bracket G', fastened to the frame in rear of the main shaft, and a pivoted jaw g^5 , located below and coöperating with the jaw g^4 . Jaw g^5 is pivoted at g^6 to bracket G' and has an enlarged tubular upper 45 end or head g^7 . Through the tubular end extends a screw-threaded pin g^{10} , swiveled to or bearing upon at its inner end a short bar g^8 , which slides in a squared socket in said end g^7 and has an antifriction - roll which bears 50 upon the periphery of disk B and coöperates with a cam-depression g^9 therein. The outer end of the screw-pin g^{10} has a suitable manipulating-head g^{11} . The major portion of the weight of the pivoted jaw g^5 is so disposed as 55 to cause the jaw normally to fall away from stationary jaw g^4 , thus permitting the free passage of the thread and to cause the roll to tend to fall into the cam-depression g^9 . Obviously a spring to cause the same result suitably co- 60 operating with the pivoted jaw would be a mechanical equivalent.

The work is punctured and fed by the awl a, the mechanism for actuating which in its best form to accomplish the two functions 65 perfectly and easily is clearly shown in Figs.

5, 6, and 7. In these figures the awl a is shown as provided with a flat angular shank a', held by a screw to the upper or outer end of a supporting pin or post a², carried by a short horizontal shaft a³, journaled in the tubular needle-carrying shaft n. The awl-post a² extends through and plays in the slot n⁷ of the needle-shaft. Extending laterally from the angular shank a' is a short pin or journal a⁴, which plays freely in and is guided by a slot a⁵ in a depending head a⁶ of the awl-actuating lever a⁷. The head a⁶ is carried by a vertical pin a⁸, suitably held and rigidly clamped in the forward end of said actuating-lever a⁷. The lever a⁷ in the form shown is provided with a long journal-pin a⁹, supported by a lug a¹⁰ of a vibrating plate a¹¹, supported on the top of the upright f¹. The plate a¹¹ is longitudinally slotted about half its length and at its rear end is provided with a transverse seat into which extends a guiding pin or screw a¹², tapped into the frame. The fulcrum of the plate a¹¹ is provided by a vertical stud a¹³, extending into the slot a¹⁴. Stud a¹³ is carried by a block a¹⁵, having a screw-threaded aperture in its outer end and through which extends the adjusting-screw a¹⁶, swiveled in the bracket-arms a¹⁷. The awl-lever is actuated by a cam-groove a¹⁸ in disk A, which operates upon a roller carried by the rear end of the said lever. As 95 shown in Figs. 5 and 6, the cam-groove a¹⁸ is provided with a depression a¹⁹ and a lateral digression a²⁰, the former, aided by spring a²¹, causing a vertical oscillation of lever a⁷ and the latter causing a lateral vibration of the 100 said lever to effect when the awl is in the work the proper feeding movement. The extent of the feed movement is regulated and controlled by the adjustment of the fulcrum-stud a¹³, as 105 above described.

The operation of the machine is as follows: The needle-thread is led to the looper, as previously stated, and a bobbin or cop of the thread is placed in the bobbin-case and the latter in the holder. The machine is now 110 ready to sew, and presuming that one stitch has been made and set in the work held by the operator against the work-support and a feed movement has taken place the needle-thread will lead from the work to the looper. 115 The awl which caused the feed of the work will now be retracted, and likewise the looper. As shown in Fig. 1, the needle-lever will now be lowered by its roller running into the depression n⁸, resulting in the upward movement of the needle to pass through the work. As also shown in Fig. 1, the take-up lever is continued elevated by its roller running in the highest part of the take-up cam-groove, thus supporting the thread substantially taut. 120 The thread - grip is also shown closed, thus preventing supply of thread. Just before the needle reaches its extreme upward position of Fig. 1 the looper will have been advanced to its extreme forward position, re- 125 130

sulting in holding the thread stiffly in the path of the needle. The lead of the thread will be substantially as shown in Figs. 1 and 7. The oscillating hook will be held in position 5 inoperative. The needle-lever now rises. The needle is retracted and catches the thread in its hook and draws the same in loop form down through the work. At the same time the take-up descends, giving up the thread to 10 form the loop, and the thread-grip is opened, permitting supply. When the needle has drawn the loop to the full extent, the hook will be moved forward from the dotted to the full line position of Fig. 4, resulting in entering 15 the loop and taking it from the needle, carrying it around and spreading it over the bobbin-case. Substantially at this time the looper will be retracted and the awl in substantially its highest position will have assumed 20 laterally its penetrating plane. The awl will then be depressed by the high part of the cam penetrating the work and holding the same until a stitch is completed and will then be moved laterally to feed the work. 25 Practically at the same time the take-up will rise and the thread-grip will close upon the thread, thus enabling the take-up to fully draw the loop and set the stitch. These operations are repeated successively.

30 It will be noted by reference to Fig. 7 that when the awl descends to enter the work it moves from one extreme lateral position gradually to the other, reaching the latter just about as it enters the work; but when it 35 ascends its movement from one extreme to the other is very rapid, and the same is finished before the awl leaves the work. The arrow and line x represent the former and the arrow and line x' represent the latter movement.

40 Having thus described my invention, what I claim as novel is—

1. In a shoe-sewing machine, the combination of a needle mechanism and an awl mechanism, the awl mechanism comprising an awl 45 and means for imparting a lateral movement, a succeeding penetrating movement, and a combined feeding and withdrawing move-

ment, the withdrawing movement taking place as the needle moves forward.

2. In a shoe-sewing machine, the combination of a needle mechanism and an awl mechanism, the awl mechanism comprising an awl and means for imparting a lateral movement, a downward penetrating movement, and a lateral and upward retractive movement, the retractive movement taking place as the needle moves forward. 50

3. In a shoe-sewing machine, the combination of a needle mechanism and an awl mechanism, the awl mechanism comprising an awl and means for imparting a lateral advancing movement, a following penetrating movement, and a lateral feeding and retractive movement, the retractive movement taking place as the needle moves forward. 55

4. The combination in a shoe-sewing machine, of a needle and an awl, a tubular needle-shaft, an awl-carrying shaft journaled in the needle-shaft, the needle-shaft being cut away longitudinally and circumferentially to 70 permit downward and lateral movements of the awl.

5. In a shoe-sewing machine, the combination with an awl, of an actuating-lever, a vibrating plate to control the feed movement 75 of the awl longitudinally slotted at one end and transversely slotted at the other, each slot receiving a guide pin or stud, the pin engaged by the longitudinal slot being carried by an adjustable block, and operating means 80 for the actuating-lever, substantially as described.

6. In a shoe-sewing machine, an adjustable and regulable awl mechanism, comprising an awl with a shank having a projecting post, an 85 actuating-lever having a depending head with a slot in which lies the awl-post, substantially as described.

In testimony whereof I affix my signature in presence of two witnesses.

EUGENE SMITH.
